UNITED STATES PATENT OFFICE

144,750

DESIGN FOR AN AIRPLANE MASK

Elbert M. Wilson, Denver, Colo.

Application July 16, 1945, Serial No. 120,737

Term of patent 14 years

(Cl. D34—15)

To all whom it may concern:

Be it known that I, Elbert M. Wilson, a citizen of the United States, residing in the city and county of Denver and State of Colorado, have invented a new, original, and ornamental Design for an Airplane Mask, of which the following is a specification, reference being had to the accompanying drawing, forming part thereof.

Figure 1 is a plan view showing the mask to a small scale and showing the position on the face when the mask is in use;

Figure 2 is a plan view of the mask to a larger scale than that employed in Figure 1, showing my new design;

Figure 3 is an end elevation looking upwardly in Figure 2; and

Figure 4 is a side elevation looking towards the left in Figure 2.

I claim:

The ornamental design for an airplane mask, as shown.

ELBERT M. WILSON.
